US00D985552S

(12) **United States Design Patent** (10) Patent No.: **US D985,552 S**
(45) Date of Patent: ** May 9, 2023

(54) **ELECTRONIC DEVICE**(71) Applicant: **Apple Inc.**, Cupertino, CA (US)(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Sung-Ho Tan**, Vienna (AT); **Clement Tissandier**, San Francisco, CA (US); **Eugene Antony Whang**, San Francisco, CA (US); **Rico Zörkendorfer**, San Francisco, CA (US)(73) Assignee: **Apple Inc.**, Cupertino, CA (US)(**) Term: **15 Years**(21) Appl. No.: **29/854,314**(22) Filed: **Sep. 23, 2022****Related U.S. Application Data**

(63) Continuation of application No. 29/656,623, filed on Jul. 13, 2018, now Pat. No. Des. 964,985.

(51) LOC (14) Cl. ..... **14-02**(52) U.S. Cl. **D14/341**
USPC ..... **D14/341**(58) **Field of Classification Search**USPC ..... D14/138 AA, 138 AB, 138 AC, 138 AD, D14/138 C, 138 G, 248, 315-318, D14/341-347, 371, 374, 432, 439; D6/308, 310; D10/50, 65, 104.1; D18/6-7; D19/26, 59-60; D21/324, D21/329-330, 332
